SPRING STABILIZER

Rudolph J. Taub, Bloomfield, N. J.

Application August 27, 1937, Serial No. 161,192

7 Claims. (Cl. 5—262)

This invention relates to improvements in spring stabilizers.

Its object is to provide a simple and inexpensive device for the purpose of reinforcing the edges of spring-assemblies, of which the resilient elements are coil springs, and to resist lateral movement of such assemblies in two directions. Such "assemblies" as are referred to are in common use as bed springs, and as furniture and automobile seats, for example. In such devices it is common practice to provide a more or less rigid lower frame upon which the spiral springs are mounted, such frame having side rails which are immovable in relation to the bed-stead, chair, car 15 or other structure which supports it. The upper ends of the spiral springs are interconnected in various ways and the outer edges of the outer rows of springs are interconnected by rods or bars which are capable of limited movement under the 20 control of the springs.

Spiral springs are capable of tipping and so it is desirable to provide something to prevent this inherent tendency. Many devices for this purpose have been suggested and some have been used, but all of them have had objectionable features which it is the object of this invention to overcome.

More specifically, the object of this invention is to provide a stabilizer constructed of spring 30 metal of flat cross-section which resists lateral relative movement between its ends, with a single curved portion providing a desired relative vertical movement between its ends and with intermediate portions so shaped and arranged as to prevent inward and outward movement of the upper end during its vertical movement.

Another object is to so construct the stabilizer that it may be readily applied to spring assemblies of standard constructions.

These and other objects of my invention will 40 appear in the following specification in which I will describe a preferred form of my stabilizer, the novel features of which will be set forth in appended claims.

Referring to the drawing,

Fig. 1 is an end elevation of a spring stabilizer which is made according to and embodies my invention, together with one of the lower side rails and the corresponding upper bar of a spring assembly. The parts are shown in full lines in one position and in broken lines in another position;

Fig. 2 is a sectional view of a part of the stabilizer shown in Fig. 1, the section being taken on the line 2—2 of the latter figure;

Fig. 3 is a plan view of the parts shown in Fig. 1; and

Fig. 4 is an end elevation of some of the parts shown in Fig. 1, illustrating a modified structure.

10 designates a side rail of the lower frame of a spring assembly, such as a bed spring. This is

usually one of four members which are rigidly interconnected to form a rectangular structure which is adapted to rest on a bedstead. According to a common practice, these rails are made of angle irons. This rectangular structure is a part 5 of the frame upon which a plurality of spiral springs (one of which is shown in Fig. 1) are supported. 11 is the corresponding upper bar of the spring assembly, that is, the one above and parallel with the rail 10.

There are four of these upper bars around the outer edges of the outer rows of springs, but it is only necessary to show one of them for the purpose of clearly explaining my invention.

20 generally designates the stabilizer. This 15 comprises an upper end 21 which is affixed to the bar 11 at 12. 22 is a part which I call the "drop", which, as will be pointed out, performs an important function. It depends from the end 21 at a substantially right angle. At the lower end of 20 the drop the flat metal of which the stabilizer is constructed, is bent inwardly at less than a right angle and extends in a substantially straight line to the lower end of an open loop or bend 24 to form a leaf spring portion 23.

The bend 24 extends upwardly, outwardly and downwardly to the upper end of a shank 25 which is directed obliquely toward the inner edge of the rail 10. The metal at the lower end of shank 25 is then bent downwardly to form a lower end 26 30 which is affixed to the rail 10 at 13 by rivets or by any other suitable means.

The purpose of the drop 22 is to lower the outer end of the spring portion 23 in relation to the loop 24 so that the leaf portion 23 will be nearer the 35 horizontal than will be shank 25, and to bring the top of the loop below the upper plane of the spring assembly. It is not necessary to have a sharp bend at the lower end of the drop, as is shown in Fig. 1.

By referring to Fig. 3 it will be seen that the flat metal is offset laterally to provide a clearance at 27 between the leaf spring portion 23 and the shank 25. It is also desirable to provide a reverse offset near the ends 21 and 26, as shown, to bring 45 them into vertical alinement. This refinement, however, is not essential.

The shank 25 is preferably stiffened by having longitudinal ribs 28 pressed therein (see Fig. 2). In Fig. 4 another way of stiffening the shank is 50 shown. In this case a brace 30 is affixed to the rail 10 and to the upper part of shank 25 at 31.

It will be seen from the foregoing description that the stabilizer acts with the spiral springs to hold the bar 11 above the rail 10. As many of 55 these devices as desired may be spaced along the bars and rod and at the corners where they are joined, and these serve to reinforce the springs along the edges of the spring assembly when such reinforcement is most needed.

Another function the stabilizer performs is, because of the flatness of the metal of which it is formed, it resists longitudinal movement of the bar 11 relative to the rail 10. When additional weight is applied to the bar 11 to depress it to its broken line position 11A (Fig. 1), its movement will be in a straight vertical line A, A. This is due to the cooperative effect of the drop 22 which lowers the connection of the leaf spring portion 23 with the bar 11, and the stiffening of the shank 25 which in effect raises the connection between the rail 10 and the resilient loop 24. Consequently, the loop 24 will move inwardly, as indicated by the arrow B (Fig. 1) during the downwardly movement of the bar 11. The length, obliqueness and resiliency of the leaf spring portion 23 of the stabilizer are so proportioned that it will assume a more nearly horizontal position when depressed, to compensate for the inward movement of the loop 24.

It is to be noted that as the inner end of spring portion 23 merges into the lower part of loop 24 the downward movement of the bar 11 tends to open the loop 24 rather than to squeeze it more tightly together. This novel feature is important, as the movement of the spring does not bring adjacent parts of the device into contact with each other.

In regard to its simplicity, one of the great advantages of this device is that it is absolutely noiseless. This is because there are no relatively movable abutting parts.

I realize that the principles involved in this invention may be embodied in devices of modified form and intent no limitations other than those imposed by the following claims.

What I claim is:

1. A spring stabilizer constructed of resilient metal having a lower end adapted to be permanently affixed to a lower member of a spring assembly, a comparatively stiff shank extending upwardly and inwardly therefrom, an upper end adapted to be permanently affixed to an upper member of said assembly out of vertical alinement with the lower member of the assembly, a spring portion of greater resiliency than that of the shank extending downwardly and inwardly from said upper end, and a single loop intermediate said shank and spring portion, below the upper member of the assembly offset laterally to provide clearance between the shank and the spring portion, the inner end of the spring portion merging into the lower end of the loop.

2. A spring stabilizer constructed of flat resilient metal having a lower end adapted to be permanently affixed to a lower member of a spring assembly, a shank extending upwardly and inwardly therefrom, means for stiffening the shank, an upper end adapted to be permanently affixed to an upper member of said assembly out of vertical alinement with the lower member of the assembly, a leaf spring portion, below the upper member of the assembly extending downwardly and inwardly from said upper end, and a single loop intermediate said shank and spring portion offset laterally to provide clearance between the shank and the spring portion, the inner end of the spring portion merging into the lower end of the loop.

3. A spring stabilizer constructed of flat resilient metal having a lower end adapted to be permanently affixed to a lower member of a spring assembly, a shank extending upwardly and in-

wardly therefrom, means for stiffening the shank, an upper end adapted to be permanently affixed to an upper member of said assembly out of vertical alinement with the lower member of the assembly, a leaf spring portion extending downwardly and inwardly from said upper end, with its inclination from the vertical greater than that of the shank, and a single loop intermediate said shank and spring portion, below the upper member of the assembly offset laterally to provide clearance between the shank and the spring portion, the inner end of the spring portion merging into the lower end of the loop.

4. A spring stabilizer constructed of flat resilient metal having a lower end adapted to be permanently affixed to a lower member of a spring assembly, a shank extending upwardly and inwardly therefrom, an upper end adapted to be permanently affixed to an upper member of said assembly, a leaf spring portion extending downwardly and inwardly from said upper end, a loop intermediate said shank and spring portion offset laterally to provide clearance between the shank and the spring portion, the inner end of the spring portion merging into the lower end of the loop, and reverse offsets beyond the loop to bring the ends into parallelism.

5. A spring stabilizer constructed of flat resilient metal having a lower end adapted to be permanently affixed to a lower member of a spring assembly, a shank extending upwardly and inwardly therefrom, an upper end adapted to be permanently affixed to an upper member of said assembly, a vertical drop from said upper end, a leaf spring portion extending downwardly and inwardly from the lower end of the drop with its inclination greater than that of the shank, a loop intermediate said shank and spring portion offset laterally to provide clearance between the shank and the spring portion, and reverse offsets 40 beyond the loop to bring the ends into alinement.

6. A spring stabilizer constructed of flat resilient metal having a lower end adapted to be permanently affixed to a lower member of a spring assembly, a shank extending upwardly and inwardly therefrom, means for stiffening the shank, an upper end adapted to be permanently affixed to an upper member of said assembly, a vertical drop from said upper end, a leaf spring portion extending downwardly and inwardly from the lower end of the drop with its inclination greater than that of the shank, a loop intermediate said shank and spring portion offset laterally to provide clearance between the shank and the spring portion, and reverse offsets beyond the loop to bring the ends into parallelism.

7. A spring stabilizer constructed of flat resilient metal having a lower end adapted to be permanently affixed to a lower member of a spring assembly, a shank extending upwardly and inwardly therefrom, longitudinal ribs in said shank to decrease its resiliency, an upper end adapted to be permanently affixed to an upper member of said assembly, a vertical drop from said upper end, a leaf spring portion extending downwardly and inwardly from the lower end of the drop with its inclination greater than that of the shank, a loop intermediate said shank and spring portion offset laterally to provide clearance between the shank and the spring portion, and reverse offsets beyond the loop to bring the ends into alinement.

RUDOLPH J. TAUB.
